United States Patent Office.

W. H. CARR, OF NEW YORK, N. Y.

Letters Patent No. 93,053, dated July 27, 1869.

IMPROVEMENT IN STEAM-ENGINES.

The Schedule referred to in these Letters Patent and making part of the same.

To all whom it may concern:

Be it known that I, W. H. CARR, of the city, county, and State of New York, have invented a new and useful Improvement in Steam-Engines, of which the following is a full, clear, and exact description, reference being had to the accompanying drawing, forming part of this specification, and in which—

Figure 1 represents a side elevation of a steam-engine, constructed in accordance with my improvement;

Figure 2, a sectional elevation of the same, taken in a plane parallel to fig. 1; and

Figure 3, a sectional view at right angles to figs. 1 and 2, of certain parts connected with the admission and discharge of steam to and from the cylinder.

Similar letters of reference indicate corresponding parts.

My invention consists in the arrangement of a reciprocating cylinder, with a piston disposed to occupy a stationary position relatively to the reciprocating motion of the cylinder, by or through which the driving-power is communicated, but both hung so as to have a rocking motion on or from a trunnion or trunnions disposed beyond the stroke of the cylinder, and the piston having arranged within it, for operation in connection with suitable passages made therein or through the valve, which governs the motion of the cylinder; also, the invention includes certain details of construction and arrangement of the same for operating the engine when constructed as described.

Referring to the accompanying drawing—

A represents the frame of the engine, and

B, its working-cylinder, which is arranged to reciprocate in direction of its length, and through the intervention of levers C C', attached to a rock-shaft, D, a pitman, E, and crank F, serves to communicate the necessary motion to the driving-shaft G.

H is the piston, which occupies a stationary position relatively to the reciprocating motion of the cylinder, and is made hollow to receive within it the valve I, that working in connection with suitable ports or passages a and b, made in or through the piston, serves to control the reciprocating action of the cylinder. This valve may be of any suitable description.

The port a, in the arrangement shown, forms the exhaust, and the ports b b, the passages to opposite sides of the piston.

J is the piston-rod, which is made hollow, and is formed with a partition, c, down through it, which serves to establish inlet and exhaust-passages d and e, the inlet-passage d being in communication with the steam-space or chamber on back of the valve, and the exhaust-passage e communicating, by a connecting or bridge-passage, with the exhaust-cavity a.

These passages d and e connect, at their lower ends, with cross-passages f and g, made in a hollow rock-shaft, K, which has a partition, h, running longitudinally down it for the purpose.

This rock-shaft works in bearings i i, on the bed-plate, and has the piston-rod firmly bolted or secured to it, whereby it serves to form the trunnions for the piston and cylinder to oscillate on, to the extent of the versed sine of the arc described by the beam or lever C, with which the cylinder is connected.

This shaft K works at its one end open end against and within an adjustable packing-cap, L, that has the steam and exhaust-pipes connected with it at openings k k, which are in communication with the passages f and g.

The valve I is operated by a rod, m, arranged to run down the inlet-passage d, within the piston-rod, and in gear at its foot with a toe, n, attached to a rock-shaft, o, which receives its motion from the main shaft G, through an eccentric, r, rod, s, and crank, u.

Any other devices, however, may be used for conveying motion to the valve-rod arranged within the piston-rod.

An engine thus constructed and operating, combines efficiency with compactness, the same admitting of a comparatively short walking-beam or main lever, C, being used without forming an objectionable working-angle, and without the aid of a pitman, while an independent valve-box is dispensed with, the piston being utilized as such, and the piston-rod serving to protect the rod which operates the valve, also serving to establish inlet and exhaust-passages, thereby doing away with independent pipes or connections from the valve.

Of course any other fluid, gas, or vapor besides steam, may be used for working the engine.

The position of the engine may, if desired, be reversed or changed to that shown in the drawing.

What is here claimed, and desired to be secured by Letters Patent, is—

1. The combination of the reciprocating cylinder B with the piston H, arranged to have a stationary position in relation to the reciprocating cylinder, and both free to oscillate on or in connection with a rock-shaft, K, to which the piston-rod is attached at its outer end, or beyond the one end of the cylinder, substantially as specified.

2. The arrangement of the valve I, by which the admission and discharge of the steam to and from the working-cylinder are controlled within the piston, for operation in connection with the ports or passages a and b b, essentially as described.

3. The arrangement, with relation to the main valve and ports, of the hollow piston-rod J, constructed with diaphragm c, forming inlet and exhaust-passages d e, and terminating in a hollow oscillating bearing, substantially as shown and described.

W. H. CARR.
